DRY-SEALING ENVELOPE OR CONTAINER

Vincent E. Heywood, Worcester, Mass., assignor
to United States Envelope Company, Spring-
field, Mass., a corporation of Maine

Application September 28, 1935, Serial No. 42,617

12 Claims. (CL 229—80)

The present invention relates to dry-sealing envelopes or containers, i. e., envelopes that are adapted to be sealed by bringing areas coated with a dry-sealing adhesive into non-moistened contact.

Dry-sealing envelopes, as heretofore constructed, have been characterized by the application of dry-sealing adhesive to different correspondingly shaped areas, which has given rise to certain inherent difficulties in the manufacture and handling of the same. In order to prevent premature contact of the dry-sealing adhesive coated areas of such envelopes prior to their loading and sealing, it has been necessary to provide either extra flaps, or to perform special folding operations, with resulting increase in the cost of manufacture. Furthermore, the utilization of extra flaps and special folding necessitates unaccustomed manipulations of such envelopes by their users in order to bring the adhesive areas into contact for sealing.

According to the present invention, there is provided an improved dry-sealing envelope or container particularly characterized by the application of a single area of dry-sealing to a blank, which adhesive area, by subsequent folding operations performed on the blank in the process of manufacture, is disposed within the completed envelope in position to provide an effective seal immediately upon bringing overlying portions of this single adhesive area into non-moistened contact, accompanied by pressure. The envelope of the present invention is especially well adapted for use as a mailing container for bulky material, since the completion of the internal seal performs the dual function of effectively closing the envelope, as well as of providing a flat portion of double thickness which may be readily written upon for addressing, even though the remainder of the envelope is extremely bulky. The above and other advantageous features of the invention will hereinafter more fully appear from the following description considered in connection with the accompanying drawings, in which—

Fig. 1 is a plan view of a blank for an envelope embodying the invention.

Fig. 2 is a view of the blank 1 provided with means for preventing premature contact between the dry-sealing adhesive areas.

Fig. 3 shows the blank folded into an envelope.

Fig. 4 is a perspective view illustrating the manner of loading the envelope and of sealing the same.

Fig. 5 is a front view of the loaded and sealed envelope.

Fig. 6 is a perspective view on an enlarged scale of the envelope of Fig. 5.

Fig. 7 is a plan view of a blank for a modified form of envelope.

Fig. 8 shows the blank of Fig. 7 folded into a complete envelope.

Fig. 9 is a front view of the envelope of Fig. 8, after loading and sealing.

Fig. 10 is a view of a container embodying the invention in the form of a finger bag.

Fig. 11 is a perspective view of the finger bag of Fig. 10, after being loaded and sealed.

Like reference characters refer to like parts in the different figures.

Referring to Figs. 1, 2 and 3, a blank 1 comprising a body portion 2, side flaps 3 and end flap 4 is provided with a relatively wide band of adhesive 5 extending continuously across one side of the blank so as to cover contiguous portions of the body 2 and both side flaps 3. The adhesive 5 is of such character that it will adhere to itself upon non-moistened contact, although it will not adhere to the material of the blank. Preferably, the adhesive is applied in the form of a dispersed rubber solution, or as natural or compounded latex, the invention also contemplating the use of other similar dry-sealing adhesives in the form of thermoplastics such as arclor resins or gallops, either alone or in combination.

After the application and drying of the adhesive 5 on the blank 1, a separator strip 6 is positioned on the blank, as shown in Fig. 2, so as to cover that portion of the adhesive 5 applied to the body 2 between the score lines 7 extending along the junctions of the flaps 3 with the body 2. The strip 6 is somewhat longer than the width of the adhesive band measured lengthwise of the blank, with one end of the strip projecting beyond the right-hand edge of the blank, as viewed in Fig. 2.

The blank 1, with the strip 6 positioned thereon as described above, is next acted upon by well-known folding and adhesive-applying instrumentalities which operate to convert the blank into a complete envelope shown in Fig. 3, with the side flaps 3 and end flap 4 adhesively united. When the flaps 3 are folded into overlying relation, the dry-sealing adhesive 5 becomes a continuous band extending completely around the inside of the envelope, with the strip 6 effectively preventing contact between overlying portions of the adhesive 5. Furthermore, the strip 6 is frictionally held in its original position

- within the completed envelope of Fig. 3, the natural tackiness of the adhesive 5 which engages opposite sides of the strip 6 tending to effectively hold the strip against removal, unless that portion 5 of strip 6a of the strip which protrudes beyond the mouth of the container should be subjected to an appreciable pull. Preferably, the protruding portion 6a of the strip is cut away along its sides, so that it has the appearance of a sealing flap, 10 and this flap may be readily folded down into the dotted line position of Fig. 3 to permit the container to be packed in the usual manner.
- As long as the strip 6 remains in the position of Fig. 3, with only its flap portion 6a protruding, it is obvious that the envelope may be packed and handled without any possibility of the dry-sealing adhesive coated areas within the envelope mouth coming into contact and thereby sealing the envelope prematurely. Furthermore, 20 with the flap 6a folded down, it is impossible for dirt and dust to enter the envelope mouth at one side to come into contact with the naturally tacky surface of the dry-sealing adhesive 5, and thereby impair the adhesion between these areas 25 when later brought into non-moistened contact. This latter feature distinguishes dry-sealing envelopes embodying the present invention from envelopes of this general character heretofore produced.
- 30 When it is desired to load the envelope of Fig. 3, it is seized between its longitudinal edges and pressure applied to open the mouth of the envelope, as shown in Fig. 4. The extended flap 6a of the strip 6 then provides an extension of 35 the mouth, which greatly facilitates the loading, particularly when small articles are to be placed therein, such as pieces of hardware. The user then, while still holding the loaded envelope in one hand, seizes the flap 6a between fingers of 40 the other hand and pulls out the strip 6 with a quick jerk, as is also indicated in Fig. 4. The loaded envelope can then be quickly and completely sealed by pressing together the walls of the container at its open end. This operation 45 brings opposed portions of the dry-sealing adhesive band 5 into contact, so that immediate adhesion results between the envelope walls over a considerable area at one end of the envelope. For the convenience of the user, the rear wall 50 of the envelope may be provided with a mark 8 and suitable printing 9 indicating that the envelope can be sealed by merely pulling out the strip 6 and pressing the walls together beyond the line 8.
- 55 The loaded and sealed envelope then appears as shown in Figs. 5 and 6, from which it is evident that the sealed area of double thickness at one end, by reason of its flat surface as compared to the remainder of the envelope, may be easily 60 written upon for the purpose of addressing the envelope. Postage stamps may also be readily applied to this same flat surface when the envelope is used for mailing purposes, and obviously the envelope will meet the ready approval 65 of postal authorities, owing to the ease with which the stamps may be cancelled.
- Referring now to Fig. 7, there is shown a modified form of blank 1', which provides a body 2', flaps 3' and 4' and a band of dry-sealing adhesive 5', all in substantially the same relation as previously described with reference to the blank 1. The blank 1' also provides a flap 10 extending for a considerable distance beyond the adhesive 5' and of substantially the same width 75 as the body 2'. The flap 10 is joined to the

body 2' by a line of perforations 11, and also provides a score line 12 located at a greater distance from the perforations 11 than is the left-hand margin of the band of adhesive 5.

In the formation of the blank 1' into an envelope, the flap 10 is first folded toward the body 2' along the perforations 11 and then is reversely folded along the score line 12, so that two layers of the flap 10 cover that portion of the adhesive 5' which is located on the body 2'. The flaps 3' and 4' are then folded from the dotted line positions of Fig. 8 into the full line positions, and are adhesively secured together to form a complete envelope. The overlying portions of dry-sealing adhesive 5' in the envelope are then 15 completely separated by reversely folded portions of the flap 10, with a considerable portion of the flap 10 extending beyond the open mouth of the envelope.

The envelope of Fig. 8 may then be loaded 20 and sealed in substantially the same manner as previously described with reference to the envelope shown in Fig. 4, it being noted that pulling out of the flap 10 extends the same, as shown in Fig. 9. The flat sealed portion of the envelope may then be readily written upon, and postage stamps applied as indicated, and any portion of the fully extended flap 10 may be written upon at the same time, as by placing shipping memoranda thereon, as indicated. The 30 flap 10 is then torn from the loaded and sealed container along the perforations 11.

Referring now to Figs. 10 and 11, there is shown a container 13 in the form of a finger bag, such as is provided customers in stores for carrying 35 articles of merchandise. The bag 13 can be readily made from a blank similar to the blank 1, with the normally closed end of the bag provided with a finger opening 14, suitably reinforced by inside patches 15, and extending through both 40 walls of the bag. As shown by the broken-away portion of Fig. 10, the normally open end of the bag is surrounded inside by a continuous band of dry-sealing adhesive 16 of the character previously described, and a strip 17 disposed between 45 overlying adhesive areas in the manufacture of the bag provides a flap 17a. When the bag 13 has been loaded through its open end, the strip 17 is removed by pulling the flap 17a, and the bag sealed by pressing the overlying adhesive areas 50 together. The loaded and sealed bag may then be reversed, as shown in Fig. 11, and readily carried by placing one or more fingers through the finger opening 14.

From the foregoing, it is apparent that by the 55 present invention there is provided an improved dry-sealing envelope or container characterized by the provision of a single area of dry-sealing adhesive disposed as a continuous band within the envelope mouth, with opposed portions normally separated by a strip, which may be readily seized and removed. In the packing and handling of the envelope or container, the protruding strip, or separator, functions as a seal flap in preventing the access of dirt and dust to the 60 dry-sealing adhesive areas, but upon removal of the strip, sealing is quickly accomplished by pressing the previously separated adhesive coated portions together to form a flat closed end of double thickness which may be readily written upon. 65

I claim:

1. An envelope or container having a single opening and provided with oppositely facing areas of dry-sealing adhesive entirely inside the envelope opening and normally maintained out of 75

- sealing contact by a removable portion partially disposed within said opening.
2. An envelope or container having a single opening and provided with oppositely facing areas of dry-sealing adhesive entirely inside the envelope opening and normally maintained out of sealing contact by a removable portion frictionally held between said areas within said opening.
- 10 3. An envelope or container open at one end and provided with oppositely facing areas of dry-sealing adhesive entirely inside the walls at the open end of the envelope and normally maintained out of sealing contact by a removable portion partially within said opening and partially projecting beyond the open end of the envelope.
- 15 4. An envelope or container open at one end and provided with oppositely facing areas of dry-sealing adhesive entirely inside the walls at the open end of the envelope and normally maintained out of sealing contact by a removable portion partially projecting beyond the open end of the envelope and partially held by friction between said areas within said opening.
- 20 5. An envelope or container open at one end and provided with oppositely facing areas of dry-sealing adhesive entirely inside the walls at the open end of the envelope and normally separated by a portion disposed therebetween, which portion upon removal from the envelope permits said areas to be pressed into sealing contact.
- 25 6. A closure for an envelope or container, comprising a continuous band of adhesive extending around the walls and disposed entirely inside of the envelope opening, said adhesive being of a character adapted to adhere to itself upon non-moistened contact, the envelope being normally maintained in open condition by an internal separator disposed between opposed portions of said band.
- 30 7. A closure for an envelope or container, comprising a continuous band of adhesive extending around the walls and disposed entirely inside of the envelope opening, said adhesive being of a character adapted to adhere to itself upon non-moistened contact, the envelope being normally maintained in open condition by a removable separator frictionally held between opposed portions of said internal adhesive band.
- 35 8. A closure for an envelope or container, comprising a continuous band of adhesive extending around the walls and disposed entirely inside of the envelope opening, said adhesive being of a character adapted to adhere to itself upon non-moistened contact, the envelope being normally maintained in open condition by a removable separator frictionally held between opposed portions of said adhesive band.
- 40 9. An envelope or container made from a blank having a band of dry-sealing adhesive applied thereto, which band by folding of the blank is disposed entirely inside the open mouth of the completed envelope, with oppositely facing portions of said dry-sealing adhesive held out of sealing contact by a separator extending partially beyond the open mouth of the envelope.
- 45 10. An envelope or container having oppositely facing portions of its walls inside an open mouth coated with dry-sealing adhesive, and a free flap extending from one envelope wall beyond the envelope mouth, said flap being initially folded with respect to said wall to dispose a portion thereof inside the envelope mouth for separating the oppositely facing dry-sealing adhesive-coated portions of the envelope walls.
- 50 11. An envelope or container made from a blank having a band of dry-sealing adhesive applied along one edge thereof and a free flap extending from said edge beyond said adhesive band, folding of said blank and flap serving to dispose said band entirely inside the open mouth of the completed envelope, with oppositely facing portions of said dry-sealing adhesive held out of sealing contact by a folded portion of said flap.
- 55 12. An envelope or container made from a blank having a band of dry-sealing adhesive applied along one edge thereof and a free flap extending from said edge beyond said adhesive band, folding of said blank and flap serving to dispose said band entirely inside the open mouth of the completed envelope, with oppositely facing portions of said dry-sealing adhesive held out of sealing contact by a folded portion of said flap, and with another portion of said flap extending beyond the open mouth of the envelope to facilitate removal of the folded portions of said flap from between said dry-sealing adhesive portions.

VINCENT E. HEYWOOD.
